FIG. 4.

J. C. P. Magwood,
inventor.
By Wilkinson & Giusta,
Attorneys.

UNITED STATES PATENT OFFICE.

JOHN CARLISLE POMEROY MAGWOOD, OF LONDON, ENGLAND.

APPARATUS FOR PLAYING RACE GAMES.

Application filed August 27, 1923. Serial No. 659,633.

To all whom it may concern:

Be it known that I, JOHN CARLISLE POMEROY MAGWOOD, student, a subject of the King of Great Britain, residing at 146 Adelaide 5 Road, Hampstead, London, England, have invented certain new and useful Improvements in Apparatus for Playing Race Games, of which the following is a specification.

10 This invention relates to apparatus for playing a race game in which models of horses or the like or other pieces (all of which I shall hereinafter refer to as "the pieces") are caused or permitted to move 15 along a course by mechanical or other means, their progress being interrupted at suitable intervals.

In carrying out this invention I employ a suitable board or base or platform provided 20 with suitable slots or guideways therein or thereon, advantageously straight parallel slots lengthwise of the board and one for each "piece", there being any desired number of the latter, say five or six.

25 Individual spring actuated means are provided for impelling each "piece" forward along its respective slot or guideway and independent means are arranged adjacent each said slot for interrupting the forward 30 progress of each "piece" at one or more points, until released in accordance with the indications of a suitable chance device. The said interrupting means according to a feature of this invention are such that although they present firm unyielding obstacles to the forward progress of the "pieces" 35 they nevertheless permit return of the "pieces" to starting position without obstruction.

40 One embodiment of my present invention is illustrated in the accompanying drawings in which:—

Fig. 1 is a perspective view of the apparatus.

45 Fig. 2 a vertical longitudinal section on line 2—2 of Fig. 4 illustrating one suitable arrangement of means for actuating the "pieces" and for arresting their progress as aforesaid.

50 Fig. 3 is a central vertical section of a spring actuated drum provided for each "piece".

Fig. 4 is a fragmentary plan view.

55 A represents an oblong box composed of wood, metal or any suitable material the top

of which is provided with longitudinally disposed slots B, one for each "piece". The slots B pass completely through the top of the box A.

Carriers C, which may be simply blocks of wood or, if desired, metal stampings, are provided with longitudinal ridges or feathers C¹ extending upwardly into the slots B and sliding freely therein. Pins C² or equivalent means are provided for mounting thereon the "pieces" D. The pins C² may extend downwardly to the bodies of the carriers C to take the place of the ridges C¹, if desired.

60 A small wheel or roller E is eccentrically mounted on a pin E¹ in a recess on the underside of each carrier C, preferably towards the forward end thereof and arranged to roll on the upper surface of the bottom of the box for the purpose of imparting an up and down movement to that end of the carrier in imitation of the galloping of a horse when the carrier is in motion along its slot.

65 Adjacent one end of each slot B a hollow drum or spool F is rotatably mounted on a pin F¹ fixed stationary in, and projecting downwardly from, the top of the box A. A coil spring F² located within the drum F has one end attached in any suitable manner to the drum and the other to the pin F¹, or the latter end may be passed through a slot in the pin F¹.

70 A braking device or friction disc G, threaded loosely on pin F¹ is pressed against the lower end of drum F by spring G¹ the pressure of which latter is adjustable by means of collar H.

75 A coiled wire or second spring J threaded tightly on pin F¹ inside spring G¹ has its inner end engaging a recess J¹ in disc G to prevent rotation of the latter when drum F is revolved by its spring (see Fig. 3).

80 A cord or flexible wire K has one end thereof attached to the drum F and the other end to the carrier C, and advantageously passes through a guiding eye K¹ located near drum F.

85 A stiff wire or rod L is rotatively mounted adjacent and parallel to each slot B and carries one or more spring catches L¹ arranged at intervals thereon successively to engage a plate or stud C³ on the carrier C when the latter is moving in the forward direction. As illustrated, these catches or obstructions comprise short lengths of wire

coiled tightly on the rods L with one end projecting and this construction has the advantage that it presents a firm obstruction to the carrier when moving forward yet 5 yields to the passage of the latter returning to starting position.

The rearward ends of these rods L project through the end A¹ of the box A and are bent around to form levers L² for rotating 10 the rods through a small angle sufficient to withdraw catches L¹ from the path of plate C³ and thus release the carrier C which is then free to move forward under the influence of the spring until engaged and held 15 back by the next catch L¹. Springs L³ serve to maintain rods L in normal position i. e. with projections L¹ in the path of plates C³, and to return said rods L to that position upon release of levers L². Metal or other 20 loops M screwed to the ends of the box A limit the movement of levers L.

Advantageously the number of obstructions L¹ is different for each "piece" in which case obviously the "odds on" or 25 "against" the several "pieces" vary in proportion.

Uprights N foldable into slots N¹ represent winning posts.

In operation, the "pieces" D are drawn 30 back to the starting end A¹ where they are held in a line by the first obstructions L¹. The several spring drums are automatically wound by thus bringing the "pieces" to "starting" position.

35 Any suitable chance device is then manipulated for example the arrow or pointer O freely mounted in a bearing in the hinged bracket or flap P is spun or rotated by hand and the "piece" indicated by number 40 when the pointer comes to rest is released by pressing the correspondingly numbered lever L². The pointer is again spun and the indicated "piece" released and so on until one or other of the "pieces" passes the 45 winning post.

If desired the difference in odds on or against the several "pieces" may be arranged by varying the size of the sectors, corresponding to the several "pieces", 50 marked on the bracket P. The number of obstructions L¹ may then, if desired, be the same for all "pieces".

If desired the bracket P may be provided 55 also with a sector marked "Disqualified", and in the case of the pointer O coming to rest at such sector during the progress of a race, the winning "piece," or if desired, the "piece" next indicated may be disqualified.

Any other suitable chance device may 60 be used, in place of the one shown, for example a die or dice, or cards etc.

In a modified arrangement of the propelling means according to this invention I 65 may employ helical springs one for each "piece", one end of each said spring being

attached to any suitable part, for example to the end A¹ of the box A, the other ends of said springs being connected by cords or wires to drums or spools, to which latter the cords K are also attached. If desired that part of each said drum or spool upon which the cord or wire K is adapted to be wound may be of larger diameter than the part upon which the spring connecting cord is wound, so that any movement of the free end of the spring will cause a greater movement of the "piece" and its carrier.

All of these said drums or spools may, if desired, be rotatively mounted on a common spindle extending across the interior of the box A near the end remote from A¹, or they may be mounted on separate spindles with either vertical or horizontal axes.

What I claim is:

1. A race game apparatus in which successive movements of the game-pieces are dictated by chance, comprising a plurality of game-pieces mounted to move substantially parallel to one another, independent actuating means for each game-piece to propel same in the forward direction, interrupting means arranged at intervals in the path of each game-piece, hand operated means for releasing each game-piece when so interrupted, and a chance device for indicating the successive releases of the game-pieces.

2. A race game apparatus comprising a box having its top provided with a number of longitudinal slots, a carrier for a game-piece arranged to travel in each slot, interrupting means normally located in the path of each carrier to intercept same at one or more points in its travel in one direction, hand-operated means for releasing each carrier in accordance with the indication of a chance device, and independent means for propelling each carrier in the forward direction.

3. A race game apparatus comprising a box having a number of longitudinal slots in the top thereof, a plurality of game-pieces mounted on carriers moving in said slots, means for positively intercepting the game-pieces from time to time in their forward progress until manually released in accordance with the indications of a chance device, and separate spring-actuated means for imparting forward movement to each game-piece independently of the others, the arrangement being such that each spring is put in tension or compression by the return of its respective game-piece to starting position.

4. A race game apparatus comprising a box having the top provided with a number of substantially straight parallel slots, game-pieces mounted on carriers arranged to travel in said slots, separate spring-actuated means connected by cords to the respec-

5 tive game-pieces, means for positively intercepting the several game-pieces at different numbers of points in their forward progress but permitting their unobstructed return to 10 starting position, means for manually releasing the game-pieces when intercepted, and a chance device for indicating the successive releases of the game-pieces.

15 5. A race game apparatus comprising a box having its top provided with a number of substantially straight parallel slots, game-pieces mounted on carriers arranged to move in said slots, means to impart an undulating motion to said carriers during their forward movement, spring actuated means for impelling said carriers in one direction and arranged to be put in tension or compression by return of the game-pieces to starting 20 position, intercepting devices normally arranged in the path of travel of said carriers, means for manually releasing said carriers,

and a chance device for successively indicating the game-pieces to be released.

6. A race game apparatus comprising a box, a number of longitudinal slots in the top of the box, game-pieces mounted on carriers traveling in said slots, separate spring-actuated spools, one for each game-piece, connected thereto by flexible means to advance said game-piece, rods rotatively mounted adjacent each slot and carrying spring projections lying normally in the path of the carriers for the game-pieces to intercept their forward but not their rearward movement, levers on the ends of said rods for partially rotating same to disengage the spring projections from the carriers, springs to return said rods to normal position and a chance device for successively indicating the game-piece to be released.

J. C. POMEROY MAGWOOD.
